UNITED STATES PATENT OFFICE.

GEORGE D. EDWARDS, OF EAST ORANGE, AND WILLIAM H. CAPEN, OF MOUNTAIN LAKES, NEW JERSEY, ASSIGNEES TO WESTERN ELECTRIC COMPANY, INCORPORATED, OF NEW YORK, N. Y., A CORPORATION OF NEW YORK.

TELEPHONE INTERCOMMUNICATING SYSTEM FOR AEROPLANES.

Application filed September 25, 1920. Serial No. 412,864.

To all whom it may concern:

Be it known that we, GEORGE D. EDWARDS and WILLIAM H. CAPEN, citizens of the United States, residing at East Orange and 5 Mountain Lakes, in the counties of Essex and Morris, respectively, State of New Jersey, have invented certain new and useful Improvements in Telephone Intercommunicating Systems for Aeroplanes, of which 10 the following is a full, clear, concise, and exact description.

This invention relates to poly-station communication systems and more particularly to communication systems for use on aircraft and the like, for local intercommunication and for distant radio signaling.

An object of the invention is to provide a communication system which will permit a radio operator on an aircraft to keep in 20 communication with a distant radio station, and at the same time to receive any necessary instructions from other members of his crew.

Another object of the invention is to provide a radio telephone system to permit one 25 member of an airplane crew to carry on telephone conversation with a distant point and to permit other members of the crew to listen in on the conversation.

30 A further object of the invention is to provide a poly-station intercommunication system which will permit one station to carry on radio communication with a distant point, and to permit two or more local stations to intercommunicate with each 35 other at the same time, without interfering with the radio communication.

40 A further object of the invention is to provide a flexible poly-station signaling arrangement, the number of stations of which can be readily increased without changing the circuit arrangements.

45 A still further object of the invention is to provide a poly-station intercommunication system in which a single induction coil may serve for all of the stations.

An additional object of the invention is 50 to provide a poly-station signaling system which may be built up of weatherproof units to operate under severe weather conditions, as, for example, in seaplanes.

According to this invention, a poly-station system is built up by associating with radio transmitting and receiving apparatus

a plurality of stations, one of which is 55 adapted to operate with the radio apparatus and all of which are arranged for intercommunication with each other. The master station, from which the radio apparatus is controlled, may switch over at will into the 60 local intercommunicating system. An operator at one of the other local stations may connect his communicating circuits to the master station receiver either when the latter is in its open neutral position or when 65 it is operating in conjunction with the radio apparatus. This local station operator may then listen in on incoming radio messages or may talk to the master station operator without causing speech to be transmitted 70 out by the radio apparatus.

In the drawing, Figure 1 is a diagram of the circuit arrangements, and Figure 2 is a perspective view of the units of a three-station airplane set.

75 Referring to Figure 1, the radio apparatus is illustrated as comprising separate receiving and transmitting antennæ, radio receiving apparatus RA, and transmitting apparatus TA. Associated with this apparatus are three operators' stations,—the master station M, and the two local stations A and B,—each indicated as a whole, in dotted lines.

The master station M is equipped with 85 a double throw switch KM which, if thrown to the left, connects the set to the radio apparatus, and if thrown to the right connects it to the interphone circuit conductors 1, 2 and 4, of which, conductors 1 and 2 comprise 90 the listening circuit and 2 and 4 the talking circuit. The master station also includes the primary winding P of an induction coil, which is permanently connected in series with a talking battery E across conductors 2 and 4, and the secondary winding S of the 95 induction coil is permanently connected to conductors 1 and 2.

The local stations A and B each comprise 100 a receiver R and a series condenser, permanently connected to the listening circuit conductors, and a transmitter T in a normally open circuit across the talking conductors. This open circuit may be closed at will by means of a double through switch K. A 105 conductor 3 is provided for communication with the master station. If a switch K is thrown to the right, it connects its transmit-

2
ter to the two talking conductors 2 and 4, if to the left, it connects the transmitter to both the talking conductors and the conductor 3.

In operation, if the operator at the master station desires to engage in radio communication, he throws his switch KM to the left. If he wishes to communicate with either of the local stations, he throws this switch to the right, thus connecting his receiver and transmitter across the listening and talking circuits, respectively. If one of the local station operators desires to listen in on the received radio communication, he throws his switch K to the left. This connects his receiver in shunt to the master station receiver. If he desires to break in on the conversation he may do so, since his transmitter circuit is closed. His remarks to the master station operator will not be transmitted out by the radio apparatus since his transmitter is entirely disconnected from the radio transmission circuit.

The local station operators may engage in conversation with each other, regardless of whether or not the master station operator is operating his radio apparatus. When a local station operator throws his switch K to the right and talks, the other local operators, whose receivers are directly connected across the listening conductors, receive the communication. To respond, another operator likewise throws his own switch K to the right. The master operator may connect his set in on this intercommunicating line at any time by moving his own switch KM to the right. It will be evident that the master operator may be in continuous radio communication with a distant station and at the same time the other members of the crew may listen in, or, without disturbing the radio conversation, may communicate with each other. At any time, they are in position to communicate with the master operator.

Whenever local communication is carried on, the microphone is in circuit with source E and primary winding P of the induction coil. This primary winding is inductively associated with winding S of the induction coil and telephone currents are repeated to the listening circuit connected to this winding. This enables a single two-winding induction coil to be used and the local station units can therefore be made very compact. When the various switches K are each in neutral position, there is no drain on the source E.

In Figure 2, the various units of the apparatus are shown in an assembly perspective,—the radio apparatus unit H, the master station unit M, and the local station units A and B, the master station having jacks marked T and R for connection with the transmitting and receiving circuit cords, respectively, of the succeeding unit and

the stations A and B each having similar jacks for connection with the operator's transmitter and head set cords. The apparatus is accordingly so designed that it may be associated with any standard radio equipment, it being merely necessary to install the master unit and as many local stations as desired and to connect each by a simple cord extension connection to the preceding unit. Each unit may be made weather-proof and the system may be readily extended as the need arises.

Although this invention has been described as embodied in a telephone system, it is obviously not so limited in its application since it is equally suitable for both telegraph and other forms of signaling. Certain features of the invention are applicable to intercommunication systems generally, without regard to aircraft or radio telephony, and it is therefore to be understood that the invention is to be limited only by the scope of the appended claims.

What is claimed is:

1. An intercommunicating system, comprising a master station set, and a plurality of local stations, each having a transmitter and receiver, means whereby said master station may engage in two-way communication with a distant station, and simultaneously each of said local stations may transmit to and receive from all of the other local stations, and means whereby said master station may listen in at will on the receiver circuits of all of the local stations together and each of the local stations may listen in on the master station, said means comprising a single circuit-closing means at each station.

2. A communicating system comprising radio apparatus, a plurality of local signal stations, a master station, means for enabling an operator at said master station to engage in two-way radio communication with a distant station, and means for enabling said local stations during the radio communication to communicate with each other and to have one-way communication with said master station including means excluding the signal currents originating at the local stations from the radio transmitting apparatus at the master station.

3. An intercommunicating system, comprising a radio transmitting and receiving apparatus, a master station set having a transmitter and receiver operatively associated therewith, and an additional set having means to listen in on the master station receiver circuit, and to transmit signals thereto during radio transmission including means excluding currents of said local communications from the radio transmitting apparatus at the master station.

4. An aircraft communication system, comprising a master operator's signaling

- set and a plurality of local station operators' sets, means whereby the master operator may engage in distant radio communication and simultaneously the local station operators 5 may engage in local intercommunication, and means whereby either said master operator or one of said local station operators may at will listen in on the receiving circuit of the other.
- 10 5. An intercommunicating system, comprising a master station set, and a plurality of local stations, each having a transmitter and receiver, means whereby said master station may engage in two-way communication 15 with a distant station, and simultaneously

said local stations may engage in two-way communication with each other, means whereby said master station may listen-in on the receiver circuits of all of the local stations simultaneously, the means whereby 20 each of said local stations may listen-in on the receiving circuits of said master station and simultaneously on the receiver circuits of all of the remaining local stations.

In witness whereof, we hereunto subscribe 25 our names this 22nd day of September A. D., 1920.

GEORGE D. EDWARDS.
WILLIAM H. CAPEN.
